UNITED STATES PATENT OFFICE

FRED H. LOFTUS, OF ALIQUIPPA, AND THOMAS N. KURTZ, OF PITTSBURGH,
PENNSYLVANIA

CHECKERWORK FOR FURNACES

Application filed January 31, 1929. Serial No. 336,375.

The present invention relates to checker-work for furnaces of various types, and has for its object to improve that construction shown in United States Patent No. 1,686,826, granted to Fred H. Loftus on October 9, 1928.

The patented Loftus construction, while one well calculated to broadly meet the needs of checker-work for furnaces, and, while from practical use has proven to be of great value, has certain structural features which are very materially and practically improved upon by the present construction, while all of the valuable principles of the Loftus patented construction are retained.

15 The purpose of the present invention is to construct the wall tiles or bricks and the checker-blocks or heat exchangers so as to prevent fracture of the tiles during manufacture, handling, or while in use and at the same time obtain a greater weight of checker- tile for a given amount of exposed surface.

Another very important object of the invention is to provide an improved checker-brick or tile for the support of check-blocks 25 of substantially keystone-shape in cross section which will offer the proper resistance to the passage of incoming air to cause it to flow through the checker-work at the proper velocity to absorb the maximum amount of heat and will also minimize interference with outgoing gases through the checker-work while absorbing the maximum amount of heat therefrom; the correlated construction of the checker-bricks and blocks serving to eliminate cross passages or openings through the brick walls or intercommunication between the narrow wells formed by the spaced vertical walls and which correlated construction makes for an increased weight and exposed 30 surface of the checker-brick and the elimination of all possibility of clogging with dust or dirt.

A further object of the invention is to provide a checker-work construction in which the checker-blocks or heat exchangers may be used interchangeably with checker-bricks of different sizes so as to be able to vary the size and angle of the draft openings between the 40 checker-blocks without the necessity of alter-

ing in any way, either in size or shape, the checker-blocks themselves.

Other objects and advantages of the invention will become apparent during the course of the following description.

In the accompanying drawings forming part of the description, and wherein like numerals are employed to designate like parts throughout the several views:

Figure 1 is a fragmentary vertical section 60 through the checker-work taken on a line extending parallel to the vertical checker walls or upon line 1-1 of Figure 3.

Figure 2 is a top plan of the same.

Figure 3 is a transverse section of the 65 checker-work taken on the line 3-3 of Figure 1.

Figure 4 is an enlarged perspective view of a section of the checker-work embodying a 70 different size checker-brick.

Figure 5 is a view similar to Figure 1 of the modified form of checker-brick, and

Figure 6 is a perspective view of the modified form of checker-brick shown in Figures 4 and 5.

Referring now more particularly to the drawings, the numeral 10 designates the spaced-apart, parallel, vertical walls of the checker-work which define relatively narrow, deep wells 11 therebetween and which usually extend longitudinally of a regenerative or blast furnace as is well understood in the art. These spaced walls 10 of the checker-work are supported upon vertically spaced, parallel, transverse rider tiles 12, which tiles 80 are supported in the well known manner upon the usual rider walls or arches not disclosed.

The vertical checker walls 10 are composed of a plurality of superposed courses 13 of checker-tiles, the courses being arranged in break-joint relation. Each of the courses consists of a plurality of refractory checker wall tiles 14 laid in end to end abutting relation, as shown in the drawings.

Each wall tile 14 consists of a substantially 95 rectangular body, the two ends of which are cut-away, preferably along the lines shown, to conform to the outer sides of a checker-block or heat exchanger 15. In the embodiment of the invention here illustrated, these 100

cut away ends provide recesses in the ends of the tile which are deeper than one-half the height of the tile for a purpose hereinafter explained. In the form here shown, these checker-blocks 15 are of substantially key-
stone-shape in cross section with the corners rounded off as at 16. The cut-away ends of the tiles 14 provide both ends of each tile with an inclined surface 17 arranged in a plane at right-angles to the vertical longitudinal plane of the tile and also provide the ends of each tile with horizontal walls 18, parallel to the top and bottom walls of the tile to form shoulders. The walls 17 and 18 are joined by a curve 19 so as to snugly fit the contour of the checker-blocks 15.

These cut-away portions of the tiles are in effect relatively deep recesses in one edge of the tile at opposite corners thereof. When the tiles are laid in a course, end to end, the perpendicular walls 20 of the ends of adjacent tiles meet or abut as shown in the drawings so that the walls 17 and 18 of contiguous tiles in the same course form a tapered or wedge-shaped seat for snugly receiving the smaller tapered ends of checker-blocks or heat exchangers 15; the inclined sides of the checker-blocks snugly fitting against the inclined walls 17 of the adjacent tiles, while the bottoms or smaller ends of the checker-blocks snugly seat upon the horizontal portions or shoulders 18 of adjoining tiles. It is, of course, understood that the tapered seats or recesses formed by the wall 17 in the adjacent checker walls 10 are arranged opposite each other so as to receive the ends of the checker-blocks 15 and support them across the narrow wells 11 defined by the checker walls. As shown in Figure 2, the checker-walls 10 also form seats or supports for the checker-blocks 15 of adjacent wells.

It is to be particularly noted that seats formed between the abutting ends of the tiles by the walls 17 and 18 are relatively deep and of sufficient depth to receive substantially the entire height of the checker-blocks 15. This is important inasmuch as it eliminates the requirement of providing deep notches or seats directly in the bodies of the tiles which have a decided weakening effect upon the tiles and frequently cause them to fracture during manufacture, use and handling thereof. This disadvantage is eliminated in the present tile because of the fact that the deep seats for the checker-blocks are provided, not in the bodies of the individual tiles, but between the meeting ends thereof, so as not to be subject to the serious objection mentioned. It will, therefore be seen, that the seats formed between the meeting ends of the tiles will receive substantially the entire height of the checker-blocks or the heat exchangers, and it results that only a very minor part of the wider portion of each checker-block will project above the tiles and

course forming such seats. This small projecting portion of the checker-block will extend only slightly into the adjacent course of tiles, where the tops of the checker-blocks are received in relatively shallow recesses or notches 21 in tiles of the superimposed course. These notches 21 are, in the present instance, less than one-third the depth of the deep recesses between adjacent tile, but, of course, the relative dimensions of the notches and recesses can be varied without departing from the scope of the claims. In order to guard against danger of fracture, the supporting surface or base of each tile 14 is provided between its ends with such a relative shallow recess or notch 21. Because of the fact that we arrange for the relatively deep notches falling between meeting ends of the tiles, and the further fact that the courses are arranged in break-joint relation, we provide for a very shallow notch or recess 21 in each tile at a point where it will eliminate or minimize the danger of fracture of the tile in manufacture, handling, or excessive changes in temperatures to which the tiles are subjected, both in their manufacture as well as when in use in the checker-work. If desired, the narrower portions of the checker blocks 15 may be arranged to project into an adjacent course of tile instead of the wider portions of the blocks, in order that the wider portions will be arranged in the relatively deep recesses or seats, while the narrower portions of the blocks will constitute the minor projecting portions adapted to be arranged in the relatively shallow notches 21. The notches 21 are, of course, constructed to snugly receive the projecting portions of the checker-blocks in adjacent courses so that tight joints will be formed around the ends of the checker-blocks in order that there may be no cross passages or openings through the checker walls 10 and, therefore, no cross currents to detract from the efficient vertical flow of air or gas in the wells, and no ledges for the accumulation of dust and dirt, which accumulation would detract from the operating efficiency of the tiles in exchanging heat. It will also be obvious that by the herein disclosed construction, the checker-blocks will be arranged in vertical staggered relationship to divide the relatively narrow, longitudinally extending wells into vertical tortuous, narrow passages, thereby causing the air currents to be split up or divided so as to effectively scrub the surfaces of the checker-work as pointed out in the Loftus patent hereinbefore mentioned. It will also be noted, from this patent, that the cross sectional shape of the checker-blocks 15 or heat exchangers plays a very important rôle in increasing the efficiency of checker-work due to the fact that they offer minor resistance to the passage of the gas through the wells in one direction and cause major resistance to

the passage of air in the opposite direction.

In order to be able to vary the size and angle of the draft openings through the checker-work between the checker-blocks, different size tiles 14 are employed and as shown in Figures 4, 5 and 6; the wall tiles 14, shown in Figures 4, 5 and 6 are not only longer than the wall tiles shown in Figure 1, but the shoulders 18 are arranged a greater distance from the bottom of the tile to accomplish the foregoing object. Nevertheless, the depth of the notches 17 in the ends of the tiles remain the same as the depth of the notches in the tile shown in Figure 1 so that the modified form 10 of tile will receive the same checker-blocks 15 that are employed in the construction of the checker-work shown in Figure 1. This is true also of the notches 21 in the bottoms of the tiles. To make it perfectly clear what we 15 mean by varying the size of the draft passages between the checker-blocks 15, it is desired to point out that we have reference to the distance between the points A—B shown in Figure 5. In this figure, according to our installation scale, this distance is approximately 25 4½ in. with a 27° opening afforded by the checker-blocks 15, while the distance between the checker-blocks in Figure 1, on installation scale, is approximately 3 in. with an 18° opening. It will, therefore, be seen that 30 the checker-blocks are interchangeable and this is a very desirable feature in the practical use of the tiles and checker-blocks in the construction of checker-work.

35 While we have shown a particular construction and believe this to be the preferred embodiment of our invention, and have shown our invention as applied to one type of furnace, it will be understood that such variations as are within the range of mechanical skill may be made without departing from the invention as defined in the appended 40 claims, and that the checker-work may be installed in all and various types of furnaces 45 to which it is adaptable.

We claim:

1. In checker-work, the combination of a series of tiles having tapered bodies providing inclined end portions in planes at right- 50 angles to the vertical longitudinal plane of the tile and laid end to end to provide tapered seats between the adjacent ends of the tiles, and heat exchangers tapered in transverse cross section seated in said tapered 55 seats.

2. In checker-work, the combination of a series of tiles laid end to end in a course, said tiles having transverse ends inclined to provide substantially tapered seats between adjacent 60 ends of the tiles, and heat exchangers of substantially tapered cross section seated in said seats and completely filling the same.

3. A checker-tile comprising a body having a notch in an edge between the ends thereof, and a reduced tapered portion upon said

body having end portions in planes at right angles to the vertical longitudinal plane of said tile and forming shoulders with said body portion.

4. In a checker-work construction, the combination of a series of tile laid in courses to form spaced vertical walls defining a narrow well, heat exchangers seated in said walls and extending across said well to divide said narrow well into vertical narrow passages, 75 and said tile and said exchangers being adjustable to different fixed relations with respect to each other to vary the size and angle of said vertical passages.

5. In checker work, the combination of a 80 series of tiles laid to provide a series of courses, tapered seats in certain of said tiles, and substantially tapered heat exchangers having major and minor portions arranged in said seats, the major portions of certain ex- 85 changers being arranged in seats of one course with the minor portions of the exchanges arranged in seats of an adjacent course.

6. In checker work, the combination of 90 a series of tiles laid to provide a series of courses, tapered seats in certain of said tiles, and heat exchangers tapered in cross section and having major and minor portions arranged in said seats, the major portions of certain ex- 95 changers being arranged in seats of one course with the minor portions of the exchanges constituting the wider parts thereof arranged in seats in an adjacent course, said minor portion of each exchanger being 100 less than one-third of the height thereof.

7. A checker tile comprising a body having one end wall provided with a recess deeper than substantially one-half the length of said wall, another wall of said body having a relatively shallow notch of less than substantially one-half the depth of said recess. 105

8. A checker tile comprising a body having its ends each provided with a recess 110 deeper than substantially one-half the height of said body, the base of said body having a notch between its ends of less than substantially one-half the depth of said first recess.

9. A checker tile comprising a body having its ends each provided with a recess deeper than substantially one-half the height of said body, the substantially upright walls of said recesses inclining and tapering upwardly from the base of the body, and said base 120 having a notch intermediate its ends of less than one-half the depth of said recesses.

10. In checker-work, a heat exchanger block, and tiles having their ends cut away to receive therebetween substantially the full 125 height of said heat exchanger block.

11. In checker-work, a tapered heat ex- 130 changer, and a checker-tile comprising a body having an end portion inclined a distance equal to substantially the full height of

the exchanger and arranged in a plane at substantially right angles to the vertical longitudinal plane of said body.

12. The combination with a series of tile 5 of different sizes, either size being laid in courses to form walls defining a well, heat exchangers seated in said walls in staggered relation and extending across said well to divide the same into vertical passages, and 10 said exchangers being interchangeable for use in conjunction with walls constructed from either size tile whereby the size and angle of said vertical passages can be varied by the use of the requisite size tile.

15 13. A checker tile comprising a body having one end wall provided with a relatively deep recess, and another wall of said body having a relatively shallow notch of less than substantially one-fourth the depth of said recess.

20 In testimony whereof we have hereunto set our hands.

FRED H. LOFTUS.
THOMAS N. KURTZ.
